UNITED STATES PATENT OFFICE.

ABEL G. STILSON, OF COBLESKILL, NEW YORK.

COVER FOR POTS.

SPECIFICATION forming part of Letters Patent No. 392,762, dated November 13, 1888.

Application filed January 17, 1888. Serial No. 201,010. (No model.)

To all whom it may concern:

Be it known that I, ABEL G. STILSON, of Cobleskill, in the county of Schoharie, State of New York, have invented certain new and 5 useful Improvements in Covers for Pots, of which the following is a specification.

This invention relates to an expansion-cover for pots and other vessels that can be quickly and conveniently adjusted to different sizes of 10 pots as required; and the invention consists of an expansible cover which is formed of a disk that is open from its center to one point of its circumference, the ends of said disk being made to overlap each other, the underlapping 15 end being provided with a guide device for keeping the ends in contact with each other, and with raised radial ribs at the edge that are engaged by a locking-spring, the inner end of which is inserted into a central opening 20 of the cover. The looped locking-spring is provided at the inner end with a fixed washer for covering the central opening of the cover, and at the outer end with a bent hook that engages the ribs of the underlapping end 25 of the cover, said spring bearing against an upwardly-bent stop or abutment of the overlapping end of the cover.

In the accompanying drawings, Figure 1 represents a top view, Fig. 2 a side view, and 30 Fig. 3 a vertical transverse section, on line x , Fig. 1, of my improved expansible cover for pots and other vessels.

Similar letters of reference indicate corresponding parts.

Referring to the drawings, A represents my 35 improved cover, which is made from a disk-shaped piece of sheet metal that is slitted radially from its center to one point of its circumference, so that the ends next adjoining the slit can be made to overlap each other on bending the disk into conical or convex shape, as shown in Fig. 3. The underlapping end of the disk-shaped cover A is provided with a wire guide-hook, a, by which it is retained in 40 contact with the overlapping end. The underlapping end is further provided with radial ribs b, as shown clearly in Figs. 1 and 2, which are engaged by a looped locking-spring, B, the inner end, d, of which is inserted into 45 a central opening, d', of the cover A, while the outer hook-shaped end, d'', engages one of

the radial ribs b of the underlapping end, so as to retain both ends of the cover firmly in position. The outer end, d'', of the locking-spring B bears on a bent-up portion, stop, or 55 abutment, e, of the overlapping end, so as to facilitate the adjustment of the latter over the underlapping end. The locking spring B is bent with one or two loops, so as to facilitate the application of the outer hook-shaped end, 60 d'', to the overlapping ends of the cover A. The inner end is provided with a disk-shaped cap, f, which covers the central opening, d', of the cover.

The locking-spring B may be readily detached from the cover for setting the cover to the proper size, and applied thereto by reinserting the inner end into the central hole of the cover and the outer hook-shaped end in one of the ribs b in the underlapping end of 70 the cover. The overlapping ends of the cover may also be locked together by the spring B without removing the same by simply taking hold of the cover at both sides of the ends, pushing the ends one over the other, and placing the hook-shaped end of the locking-spring 75 into the required rib b, as shown in Fig. 2.

I am aware that expansible covers for pots formed of a radially-slitted disk of sheet metal, in which the overlapping ends are each provided with a handle and retained in contact by suitable means, have been used heretofore, and I do not claim these features, broadly.

Having thus described my invention, I claim as new and desire to secure by Letters Patent— 85

1. The combination of an expansible cover having overlapping ends, the underlapping end being provided with radial ribs at its circumference and the overlapping end with a stop or abutment at its edge, means for holding the overlapping ends in contact with each other, and a locking-spring extending from the center of the cover to the edge and engaging the overlapping ends of the same, substantially as set forth. 90

2. The combination of an expansible cover having overlapping ends, the underlapping end having radial ribs at its circumference and the overlapping end a stop or abutment at its edge, a guide-hook for retaining the overlapping ends in contact with each other, and a locking-spring that is applied to a central 95 100

opening of the cover and provided with a hook at the outer end for engaging one of the ribs of the underlapping end of the cover, substantially as set forth.

- 5 3. The combination of an expandible cover having overlapping ends, the underlapping end being provided with radial ribs and the overlapping end with a stop or abutment at its edge, a guide-hook for keeping the overlapping ends in contact with each other, and a locking-spring the inner end of which is inserted into a central opening of the cover and

provided with a washer, while the outer hook-shaped end of the spring extends alongside of the abutment and engages one of the indentations of the underlapping end, substantially as set forth. 15

In testimony that I claim the foregoing as my invention I have signed my name in presence of two subscribing witnesses.

ABEL G. STILSON.
